Attorney.

UNITED STATES PATENT OFFICE.

LOUIS E. RICE, OF CLEVELAND, OHIO, ASSIGNOR TO THE SILVER MANUFACTURING COMPANY, OF SALEM, OHIO, A CORPORATION OF OHIO.

FEED-CUTTER ATTACHMENT.

No. 864,691.

Specification of Letters Patent.

Patented Aug. 27, 1907.

Application filed May 1, 1907. Serial No. 371,331.

To all whom it may concern:

Be it known that I, Louis E. Rice, a citizen of the United States, residing at Cleveland, in the county of Cuyahoga and State of Ohio, have invented certain 5 new and useful Improvements in Feed-Cutter Attachments; and I do hereby declare that the following is a full, clear, and exact description of the same, reference being had to the accompanying drawing, making a part of this specification, and to the numerals and figures of 10 reference marked thereon, in which—

Figure 1 is a perspective view showing portions of the upper and lower feed rolls in proper relative position with reference to the shear plate and cutter head. Fig. 2 is a detached view showing a portion of one of the 15 end plates. Fig. 3 is a view showing a portion of the shear plate and the feed roll disks separated from each other and illustrating one of the feed supporting plates.

The present invention has relation to feed cutter attachments, pertaining more particular to the lower 20 feed roll and it consists in the novel arrangement hereinafter described and particularly pointed out in the claims.

Similar numerals of reference indicate corresponding parts in all the figures of the drawing.

25 In the accompanying drawing, 1 represents the lower feed roll shaft upon which is securely mounted the angular shaft or bar 2, but I do not desire to be limited to the shaft 1 and the bar 2, being formed in separate parts as it will be understood that it is simply mechanical to make said parts integral and provide the ends with suitable journals. Upon the bar 2 are mounted any desired number of toothed disks 3, which toothed 30 disks are formed of a diameter equal to the diameter of the feed roll proper. The disks 3 are provided upon 35 one of their sides with the disk flanges 4, which disk flanges are formed of a width equal to the thickness of the plates 5 or substantially so and the flanges 4 are adapted to be entered in the apertures 6 in said plates when the parts are assembled as shown in Fig. 1. 40 The shear plate 7 may be provided with the flange 8, which flange is for the purpose of holding the forward ends of the plates 5 in proper relative position with reference to the shear plate 7. The plates 5 are each provided with the recesses 9, which recesses receive the 45 flange 8, and when the plates are properly assembled the portions 10 of the plates 5 will be located above and upon the shear plate 7. In cutting many kinds of material it is liable to be drawn down between the

back of the shear plate by reason of the rotation of the feed rolls, but by providing the plates 5 and locating 50 them between the toothed disk 3, the material will be prevented from being drawn between the shear plates and the feed roll by reason of the extensions 10 spanning or bridging the space between the periphery of the feed roll proper and the back face of the shear plate. 55 The end toothed disks 11 are preferably formed with the lateral flanges 12, which lateral flanges constitute a recess or socket for the disk flange 13 formed upon the end plates 14. The end plates 14 are of course connected to the frame of the feed cutter or to the shear 60 plate 7 in the usual manner, the cutter head 15 may be of the form shown or it may be of any other desired form as the cutter head within itself forms no particular part of the present invention, except that a cutter head of some kind must be used. 65

The toothed disks are separated at their peripheries for the purpose of providing room for the interposed plates, which plates are extended beyond the toothed disks and constitute what might be termed fingers adapted to support the material during the time it is 70 passing from the feed roll disks to and upon the shear plate.

Having fully described my invention what I claim as new and desire to secure by Letters Patent, is—

1. In an attachment for feed cutters, the combination 75 of a shaft suitably journaled, a feed roll made up of a series of toothed disks, with plates located between the series of toothed disks, and a shear plate held in fixed position, the said plates being located intermediate of the toothed disks extending over and upon the said shear plate, 80 substantially as and for the purpose specified.

2. In a feed roll for fodder cutters, the combination of a shaft suitably journaled, toothed disks mounted upon said shaft, a shear plate held in fixed position, and a series 85 of plates interposed between the toothed disks and adapted to span the space between the shear plate and the feed roll, substantially as and for the purpose specified.

3. In an attachment for feed cutters, the combination of a shaft suitably journaled, a feed roll consisting of toothed disks mounted upon said shaft, and spaced from each 90 other, plates located between the toothed disks, a shear plate, said shear plate located adjacent to the feed roll, said interposed plates having fingers adapted to support the material between the shear plate and the feed roll.

In testimony that I claim the above, I have hereunto 95 subscribed my name in the presence of two witnesses.

LOUIS E. RICE.
